AUTOMOBILE DOOR LOCK

Roy H. Dean, Detroit, Mich., assignor to Ternstedt Manufacturing Company, Detroit, Mich., a corporation of Michigan

Application June 7, 1937, Serial No. 146,828

6 Claims. (Cl. 292—164)

This invention relates to an automobile door lock and more particularly to an automobile door lock which is locked from inside the automobile by manipulation of the remote control door handle.

It is the object of this invention to produce an improved arrangement for locking a door lock of the general type shown in the Andersen-Bowlus Patent No. 2,039,873, by manipulation of the inside remote control door handle.

In the drawings:

Fig. 1 shows a general assembly of the lock and remote control handle with the lock unlocked.

Fig. 2 is a detail fragmentary view of a portion 15 of the lock.

Figs. 3, 4 and 5 are detail views showing in sequence the movements of the lock parts in the locking and unlocking of the lock.

Referring more particularly to the drawings 20 the invention is shown applied to the type of lock shown in the Andersen-Bowlus Patent No. 2,039,873. The principal parts of the lock are the same as that shown in the above referred to patent and comprise a lock frame 1, sliding bolt 2, 25 outside rollback 3, and a bolt spring 4 for projecting the bolt 2. The spring 4 is carried by the bolt according to the teaching of the Flynn Patent No. 1,857,684. A connector 5 is pivotally carried as at 50 by the swinging lever 6 and 30 serves to connect the outside rollback 3 with the bolt 2. The connector 5 has an outwardly turned lug 7 which slidably engages the shifting lever 8 in the slot 9. The shifting lever 8 is pivoted on the frame 1 by the pin 10 and is held in one or 35 the other of its positions by the over-center spring 12, one end of which is connected to lever 8 as at 51 and the other end to the frame 1 as at 52 in the same manner as shown and described in the Andersen-Bowlus patent supra. Thus, shifting 40 of the lever 8 causes the connector 5 to engage or disengage the bolt 2 thereby connecting or disconnecting the outside rollback 3 from the bolt 2.

Since it is the object of this invention to utilize 45 the inside remote handle for locking and unlocking the lock, to this end the remote handle 13 is carried by the spindle 14 which is rotatably mounted on the remote handle support plate 15. The spindle 14 has fixed thereon the retracting 50 lever 16 which is connected to the sliding retractor plate 17 by the link 18. The link 18 is pivotally connected at one end to the lever 16 and at the other end to the sliding retractor plate 17. The sliding retractor plate 17 has a 55 lost motion connection with the bolt 2 in the

form of a pair of pins 19 and 20 fixed on the bolt 2 which slidably engage the plate 17 in the elongated slots 21 and 22. A pivoted cam plate 23 is pivotally supported on the rivet 24 which is fixed to the latch frame 1.

A wire spring 25 is fixed at one end to the latch frame as at 26 and has its other end turned inwardly as at 27 for engagement with the cam plate 23 in the slot 28. The spring 25 yieldably retains the cam 23 in center or neutral position 10 as shown in Fig. 1.

The cam plate 23 is provided with lobes 31, 32 and 33 which are arranged for coaction with the lug 34 of the shifter lever 8 and the depending lug 35 on the sliding plate 17 as described 15 below.

The operation of the lock is as follows: As shown in Fig. 1, the lock is unlocked and counterclockwise rotation of the outer rollback 3 will shift the connector 5 to the left. Since connector 5 is in raised position it will abut shoulder 36 on the bolt 2 and as it travels leftward retract the bolt. In unlocked position the lever 16 is in neutral position, as shown in the full lines in Fig. 1, and is held in this position by 20 the remote handle return spring 47 in the conventional manner. To retract the bolt 2 from the inside, the remote handle 3 is swung counterclockwise from neutral position to open position, as shown in Fig. 1, which causes the lever 16 to 25 retract the link 18 and slide plate 17. As the slide plate 17 moves leftward it acts through the pins 19 and 20 to retract the bolt 2.

To lock the lock, that is, make the outside rollback ineffective to retract the bolt, the remote 35 handle 13 is swung clockwise from neutral position to the position indicated in the dotted lines, Fig. 1. This swings the lever 16 clockwise to the position indicated by the dotted lines 37. The lever 16 is held in this position by the over-center 40 spring 38 of the hairpin type which has one end connected to the lever 16 as at 39 and the other end connected to the support plate 15 as at 40. As the lever 39 swings clockwise the link 18 and shifter plate 17 are shifted to the right as indicated by the arrow, Fig. 3. As the plate 17 slides to the right, the lug 35 strikes lobe 31 and swings the cam 23 clockwise about its pivot 24 as indicated by the arrow. This causes the lobe 32 to engage the lug 34 on the shifter lever 8 and 50 swing the shifting lever 8 counter-clockwise or downwardly as also indicated by the arrow, Fig. 3. As the shifter lever 8 swings downwardly it acts through the lug 7 to swing the connector 5 55 downwardly out of engagement with the shoulder 55

36 on the bolt 2 to the position shown in Fig. 4. As the cam plate 23 turns clockwise, it stresses the spring 25. As soon as the lobe 31 clears the lug 35, the spring 25 rotates the cam counter-clockwise back to neutral position shown in the dotted lines, Fig. 4 and full lines, Fig. 5. At this time the lug 35 is positioned between lobes 31 and 32 and lug 34 has been shifted to a position adjacent the lobe 33. The lock is now locked and rotation of the outside door handle and outside rollback merely shifts connector 5 to the left without retracting the latch bolt as described in the Andersen-Bowlus Patent No. 2,039,873.

To unlock the lock the remote handle is swung clockwise from the position indicated in the dotted lines, Fig. 1, to neutral position. This, as indicated by the arrow in Fig. 5, causes plate 17 to slide leftward along bolt 2. At this time the lug 35 engages lobe 31 and rotates the cam plate 23 counter-clockwise thereby stressing spring 25. As the cam 23 rotates counter-clockwise the lobe 33 engages lug 34 on shifter lever 8 and shifts the lever 8 upwardly as indicated by the arrow, Fig. 5. As the lever 8 moves upwardly, it acts through lug 1 to shift connector 5 from the position shown in the full lines to the dotted line position in Fig. 5 so that the connector 5 is again in position to contact abutment 38 on the bolt 2. As the sliding plate 17 travels to the left, lug 35 clears lobe 31 and spring 25 again returns cam plate 23 to the position shown in Fig. 1. The over-center spring 12 yieldably holds the shifter lever 8 in locked and unlocked position in the manner described in the Andersen-Bowlus patent supra. As the shifter lever 8 shifts the connector 5 from locked to unlocked position and vice versa, the over-center spring 12 during the initial portion of the travel of the lever 8 resists this movement and then snaps over-center and assists the movement.

I claim:

1. An automobile door lock comprising in combination a retractable latch bolt, an outside rollback, a shiftable connector between said rollback and bolt, a shifter lever operatively connected to said connector for shifting the same into and out of engagement with said bolt whereby when the connector is shifted into engagement with the bolt turning of the outside rollback retracts the bolt, a remote inside handle, operative connections between the remote handle and latch bolt including a plate having a lost motion connection with the said bolt, said plate including a portion adapted to operate said below-mentioned cam, a cam pivoted in the path of travel of the said portion of said plate and said shifter lever whereby when the remote handle is swung in bolt non-retracting direction the plate engages the cam to pivot the same and the cam shifts the shifter lever to disengage the connector from said bolt whereby rotation of the outer rollback is ineffective to retract the bolt.

2. An automobile door lock comprising in combination a retractable latch bolt, an outside rollback, a shiftable connector between said rollback and bolt, a shifter lever operatively connected to said connector for shifting the same into and out of engagement with said bolt whereby when the connector is shifted into engagement with the bolt turning of the outside rollback retracts the bolt, a remote inside handle, operative connections between the remote handle and latch bolt including a plate having a lost motion connection with the said bolt, said plate including a portion adapted to operate said below-mentioned

cam, a pivoted cam having a plurality of lobes, a spring connected to said cam for yieldably maintaining the same in center position, one of said lobes being positioned in the path of travel of said portion of said plate and the other two lobes being positioned one on each side of said shifter lever whereby when the remote handle is swung in bolt non-retracting direction the said portion of said plate engages the first mentioned lobe on the said cam to pivot the cam and one of the other lobes shifts the shifter lever to disengage the connector from the said bolt whereby rotation of the outer rollback is ineffective to retract the bolt.

3. An automobile door lock comprising in combination a retractable latch bolt, an outside rollback, a shiftable connector between said rollback and bolt, a shifter lever operatively connected to said connector for shifting the same into and out of engagement with said bolt whereby when the connector is shifted into engagement with the bolt turning of the outside rollback retracts the bolt, a remote inside handle, operative connections between the remote handle and latch bolt including a plate having a sliding lost motion connection with the said bolt, said plate including a portion adapted to operate said below-mentioned cam, a pivoted cam having a plurality of lobes, a spring connected to said cam for yieldably maintaining the same in center position, one of said lobes being positioned in the path of travel of said portion of said plate and the other two lobes being positioned one on each side of said shifter lever whereby when the remote handle is swung in bolt non-retracting direction the said portion of said plate engages the first mentioned lobe on the said cam to pivot the cam and one of the other lobes shifts the shifter lever to disengage the connector from the said bolt whereby rotation of the outer rollback is ineffective to retract the bolt.

4. An automobile door lock comprising in combination a retractable latch bolt, an outside rollback, a shiftable connector between said rollback and bolt, a shifter lever operatively connected to said connector for shifting the same into and out of engagement with said bolt whereby when the connector is shifted into engagement with the bolt turning of the outside rollback retracts the bolt, a remote inside handle, operative connections between the remote handle and latch bolt including a plate having a sliding lost motion connection with the said bolt, said plate including a portion adapted to operate said below-mentioned cam, a pivoted cam having a plurality of lobes, a spring connected to said cam for yieldably maintaining the same in center position, one of said lobes being positioned in the path of travel of said portion of said plate and another lobe being positioned to swing into contact with the said shifter lever whereby when the remote handle is swung in bolt non-retracting direction the said portion of said plate first engages the first mentioned lobe on the said cam to pivot the cam and then slides clear of the said lobe whereupon the spring returns the cam to its initial position and whereby the second lobe during the pivoting of the said cam shifts the shifter lever to disengage the connector from the said bolt to render the rollback ineffective to retract the bolt.

5. An automobile door lock comprising in combination a retractable latch bolt, an outside rollback, a shiftable connector between said rollback and bolt, a shifter lever operatively connected to said connector for shifting the same into and out

of engagement with said bolt whereby when the connector is shifted into engagement with the bolt turning of the outside rollback retracts the bolt, a remote inside handle, operative connections between the remote handle and latch bolt including a plate having a sliding lost motion connection with the said bolt, said plate including a portion adapted to operate said below-mentioned cam, a pivoted cam having a plurality of lobes, a spring connected to said cam for yieldably maintaining the same in center position, one of said lobes being positioned in the path of travel of said portion of said sliding plate and the other two lobes being positioned one on each side of said shifter lever and each arranged to swing into engagement with the said shifter lever whereby when the remote handle is swung in bolt non-retracting direction the said portion of said sliding plate first engages the first mentioned lobe on the said cam to pivot the cam and then clears the said lobe whereupon the said spring returns the cam to neutral position, one of the said other lobes upon the turning of the said cam shifting the shifter lever to disengage the connector from the said bolt whereby the outside rollback is ineffective to retract the bolt and whereby when the remote handle is swung in bolt retracting direction the said portion of said sliding plate engages the first mentioned lobe to turn the cam in the opposite direction and the third lobe now shifts the shifter lever to engage the connector with the bolt to render the outside rollback effective to retract the bolt.

6. An automobile door lock comprising in combination a retractable latch bolt, an outside rollback, a shiftable connector between said rollback and bolt, a shifter lever operatively connected to

said connector for shifting the same into and out of engagement with said bolt whereby when the connector is shifted into engagement with the bolt turning of the outside rollback retracts the bolt, a remote inside handle, operative connections between the remote handle and latch bolt including a plate having a lost motion connection with the said bolt, said plate including a portion adapted to operate said below-mentioned cam, a pivoted cam having a plurality of lobes one of which is positioned in the path of travel of said portion of said plate, a spring connected to said cam for yieldably maintaining the same in center position and for returning the cam to center position each time the first lobe clears the said portion of said plate whereby when the remote handle is swung in bolt non-retracting direction the first of said lobes is adapted to swing clear of said plate after initial contact with the plate during travel of the latter in bolt non-retracting and subsequently in bolt retracting directions and whereby when the remote handle is swung in bolt non-retracting direction the said portion of said plate first engages the first mentioned lobe to pivot the cam and then clears said lobe and the second lobe shifts the shifter lever to disengage the connector from the said bolt to render the outer rollback ineffective and whereby when the remote handle is swung in bolt retracting direction the said portion of said plate again engages the first mentioned lobe on the cam to pivot the cam in the reverse direction and the third lobe now shifts the shifter lever to reengage the connector and the bolt to render the outside rollback effective.

ROY H. DEAN.
